UNITED STATES PATENT OFFICE.

ABBOTT LORING, OF BOSTON, MASSACHUSETTS.

DESIGN FOR AN ATOMIZER.

SPECIFICATION forming part of Design No. 28,976, dated July 5, 1898.

Application filed June 8, 1898. Serial No. 682,963. Term of patent 14 years.

To all whom it may concern:

Be it known that I, ABBOTT LORING, a citizen of the United States, residing at Boston, in the county of Suffolk and State of Massachusetts, have invented and produced a new and original Design for Atomizers, of which the following is a specification, reference being had to the accompanying drawings, forming part thereof.

10 Figure 1 is a side view of an atomizer, showing my new design. Fig. 2 is an edge view. Fig. 3 is a vertical sectional view on line 3 3 of Fig. 4, which shows a top plan view of the atomizer.

15 As shown in the drawings, the leading or material feature of my design consists of the round and tapered nose-piece A and the flattened and upwardly-tapered mouthpiece B, said mouthpiece having a rib b at the junction of the mouthpiece and nose-piece.

20 In outline the body a of the atomizer is of

oval shape in horizontal cross-section, the nose-piece extension A being cylindrical and tapered. The detachable mouthpiece is rounded at its base portion near the rib b and flattened at its upper end. 25

a' a' are air-inlets through the walls of the body a.

a² is a screw-cap, and a³ a plug.

Having described my invention, what I 30 claim as new, and desire to secure by Letters Patent, is—

The design for an atomizer as herein shown and described.

In testimony whereof I have signed my 35 name to this specification, in the presence of two subscribing witnesses, on this 19th day of March, A. D. 1898.

ABBOTT LORING.
